UNITED STATES PATENT OFFICE

152,511

DESIGN FOR A SHOE

Josephine Brintz Whatley, Fluvanna, Tex.

Application July 9, 1948, Serial No. 147,450

Term of patent 7 years

(Cl. D7—7)

To all whom it may concern:

Be it known that I, Josephine Brintz Whatley, a citizen of the United States and a resident of Fluvanna, Texas, have invented a new, original, and ornamental Design for Shoes, of which the following is a specification, reference being had to the accompanying drawing, forming part thereof, in which:

Fig. 1 is a perspective view of one side of a shoe; and

Fig. 2 is a perspective view of the other side of the same, showing my new design.

I claim:

The ornamental design for a shoe, substantially as shown.

JOSEPHINE BRINTZ WHATLEY.
